(57) **CLAIM**

I claim, the ornamental design for a sole for footwear, as shown and described.

DESCRIPTION

FIG. 1 is a bottom view of a sole for footwear, showing my new design;

FIG. 2 is a perspective view thereof;

FIG. 3 is another perspective view thereof;

FIG. 4 is a side view thereof;

FIG. 5 is an opposite side view thereof;

FIG. 6 is a front view thereof;

FIG. 7 is a rear view thereof; and,

FIG. 8 is a top view thereof.

1 Claim, 8 Drawing Sheets
